UNITED STATES PATENT OFFICE.

SIGMUND HONIG, OF NEW YORK, N. Y.

RAZOR-SHARPENER.

1,077,934

Specification of Letters Patent. Patented Nov. 4, 1913.

Application filed October 18, 1912. Serial No. 726,442.

To all whom it may concern:

Be it known that I, SIGMUND HONIG, a citizen of the United States, and resident of the city of New York, in the county of New York and State of New York, have invented certain new and useful Improvements in Razor-Sharpener, of which the following is a specification.

This invention relates to improvements in 10 razor sharpeners and is more especially designed for honing and stropping razor blades for safety razors.

The primary object of the invention is the provision of an inexpensive machine 15 capable of holding any manner of razor or razor blade in conjunction with honing and stropping surfaces readily manipulated thereon by the operator.

While the main object of the device is to 20 provide a machine in which any razor blade may be readily inserted for sharpening and one in which the honing and stropping operation is accomplished thereby, it is also designed to provide a holding means for 25 positioning either side of the blade so that it may be operated upon by separate honing and stropping means, which latter are automatically shifted into and out of operative positions.

30 A simple and inexpensive machine is provided in which a razor blade is inserted and upon the turning of a crank a plurality of honing and stropping rollers are set in motion which are automatically brought 35 into contact with the blade in succession.

With these objects in view and others that will appear as the nature of the invention is better understood, the same consists in the novel combination and arrangement of 40 parts hereinafter fully described, illustrated in the accompanying drawings and pointed out in the appended claims.

In the drawings forming a part of this application and in which like numerals of 45 reference designate corresponding parts throughout the several views:—Figure 1 is a central vertical sectional view of the device with a safety razor blade positioned therein. Fig. 2 is a central vertical transverse sectional view thereof. Fig. 3 is an 50 end elevation of the machine. Fig. 4 is a top plan view of the blade holding device detached. Fig. 5 is a detail sectional view of a portion of the shifting device taken

upon line 5—5, Fig. 3, and Fig. 6 is a detail view of the adjustable locking means.

Referring more in detail to the drawings, the upright supports 10 oppositely arranged are adapted for journaling the crank shaft 11 operable by the handle 12 and upon 15 which by means of the screw 13 there is rigidly secured the internal gear wheel 14 having the teeth 15.

Loosely journaled upon the shaft 11 is positioned the spool 16 with the end disks 17, 18 and in which are journaled sharpening and polishing rollers 19. Said rollers 19 are capable of revolving individually, this motion being effected by a gear 20 supplied upon the projecting end of each roller 20 adjacent the spool end 18, each of said gears being constantly in mesh with the inner rack teeth 15. The coarseness and formation of the rollers 19 may be such as is desirable for use in connection with whatever blades are desired to be sharpened, for instance one of said rollers may be a honing stone and the other three rollers herein illustrated constructed as stropping and smoothing blades of different degrees of softness, 25 and while four rollers are herein shown, it is obvious that a greater or smaller number may be employed.

A removable cross piece 21 is provided with end contracted portions 22 whereby 30 the same is readily removed from the seating slots 23 at the top of each of the standards 10, it being noted that the said cross piece 21 is adapted for removably positioning the razor blade 24 in its operative position with respect to the rollers. As a means for securing the blade upon the cross piece 21 there is provided the stationary block 25 upon one face thereof and against which the blade is adapted to be placed, while an 35 opposite block 26 is longitudinally movable for clamping the blade under adjustment of the set screw 27. This positioning of the blade is well illustrated in Fig. 1, it being evident that the parts employed are of such 40 proportions as to allow the blade to be contacted by the rollers, while parallel projecting arms 28 carried by the cross piece are provided with shiftable weight members 29 whereby the degree of frictional contact of 45 the blade with the rollers is accurately regulated. Further, the cross piece is partially rotatable so that the blade may be

positioned with either face thereof adjacent the rollers. The stationary block 25 is preferably divided as best shown in Fig. 4 to provide an interrupted portion 25' adapted 5 to receive the tang of a razor blade of the ordinary construction while it will be evident that in using the wafer blades of safety razors such blades will be clamped between the adjacent faces of the blocks as 10 shown in Fig. 1.

The operation of the device as above explained will be evident. By turning the shaft 11 the internal rack 14 is revolved whereby the gears 20 mesh therewith and 15 are all simultaneously turned to propel each of the rollers, the one only in the proper position contacting the blade 24.

The spool end 17 is provided between each two of the rollers with two slots 30 20 adapted to register with and receive the prongs 31 which project either side of the adjacent supporting member 10 and are carried by the rocking lever 32 pivoted at 33 to the said support. It will be evident that 25 by depressing the free end of said lever 32 the prongs 31 will be removed from said slots and the spool thereby released and then turned by the turning of the shaft 11 until the prongs again lock the same.

30 A gear 35 preferably having about 20 teeth upon its periphery is journaled upon the stub shaft 36 of the support and is turned by a one cog pinion 37 upon the free end of the shaft 11. One or more adjustable cam engaging devices 38 are positioned upon said gear 35 so placed as to contact the sloping sides 34 of the free end of the lever 32 whereby a turning of the wheel 35 results in engaging said lever end by 35 each of said members 38 upon each revolution thereof. An expansion spring 49 retains the lever end having the sides 34, in an elevated position with the prongs 31 in normal locking engagement with the spool.

40 In the operation of the device a turning of the handle 12 results in rotating the roller upon the blade and upon each turn of the shaft 11 and its pinion 37 the gear 35 is shifted one cog so that upon a predetermined number of turns of the handle one of the engaging devices 38 will depress the lever end 34, thus unlocking the spool which 45 will thereupon rotate until stopped by the engaging prongs 31, which latter thereby 50 lock the spool with the next succeeding roller in position to engage and act upon the razor blade. A continuous turning of the handle 12 therefore successively brings all the rollers in contact with the blade for 55 performing their successive work thereon of sharpening and polishing.

As noted in Fig. 5 the engaging members 38 are adjustable and may be mounted in bushings 39 retained by the winged nuts 40.

Having thus described the invention and 65 in what manner the same is designed for use, what is claimed as new and desired to be protected by Letters Patent of the United States is:

1. A razor sharpener comprising a journaled spool, a plurality of sharpening means upon said spool, a blade support, a locking member adapted to engageably position said spool with said sharpening means thereon successively in operative position respecting 70 said blade support, and means including a gear and a one-toothed pinion adapted to intermittently actuate said locking member during the continuous revolution of said spool.

2. A device of the class described, opposite side supports, a crank shaft journaled therein, a spool journaled upon said shaft, a plurality of sharpening rollers journaled in the opposite sides of said spool, means 85 for turning each of said rollers separately upon a rotation of the shaft, a razor blade support mounted upon the top of said side supports and means for automatically positioning and locking successively the said 90 rollers in operative relation to said blade support.

3. A device of the class described, opposite side supports, a crank shaft journaled therein, a spool journaled upon said shaft, 95 a plurality of sharpening rollers journaled in the opposite sides of said spool, an internal rack secured to said shaft and gear connections between the latter and said rollers, a pivoted locking means upon one of said supports adapted to intermittently engage said spool, and means for operating said locking means.

4. A device of the class described, opposite side supports, a crank shaft journaled 103 therein, a spool journaled upon said shaft, a plurality of sharpening rollers journaled in the opposite sides of said spool, an internal rack secured to said shaft and gear connections between the latter and said rollers, 110 a pivoted locking means upon one of said supports adapted to intermittently engage said spool, a one toothed pinion upon the free end of said shaft, a stub shaft upon one of said supports, a gear upon said stub shaft 115 meshing with said one toothed pinion, and means carried by said gear for engaging said locking lever.

5. A device of the class described, comprising parallel supports, a crank shaft journaled through said supports, a spool journaled upon said shaft, four sharpening rollers journaled in the opposite sides of said spool, operating means between said shaft and rollers, a blade positioning support on 120 the parallel supports, a pivoted locking member adapted to engageably position said spool with said rollers successively in oper-

ative position respecting said blade support, and means including a gear and a one toothed pinion adapted to intermittently actuate said locking lever during the continuous revolution of said shaft.

Signed at the city of New York, in the county of New York, and State of New

York, this 11th day of September, A. D. 1912.
